COMBINATION LOCK

Roscoe E. Lehman, Hagerstown, Md.

Application May 27, 1948, Serial No. 29,573

10 Claims. (Cl. 70—295)

1

The object of the invention is to provide a combination lock in which the combination may be quickly changed, if desired, or so arranged that few or numerous steps may be made necessary for its operation; to provide a combination lock in which, if a mistake be made in carrying out the several steps, the operating means may be returned instantly to their original positions; to provide, in such a construction, for the actuation of any or all of the control elements in such a manner that the device may be locked so as not to be releasable by carrying out any possible combination steps; and generally to provide a combination lock which is of simple construction, so that it may be manufactured comparatively cheaply, and which is of sturdy form, so that failure in service is a remote possibility.

With this object in view, the invention consists in a construction and combination of parts of which preferred embodiments are illustrated in the accompanying drawings in which:

Figure 1 is a front elevational view of one form of the invention;

Figure 2 is a rear elevational view of the structure of Figure 1;

Figure 3 is a side elevational view of the structure of Figure 1;

Figure 4 is a sectional view on the plane indicated by the line 4—4 of Figure 1;

Figures 5 and 6 are sectional views on the planes indicated respectively by the lines 5—5 and 6—6 of Figure 4;

Figure 7 is a detail sectional view in the plane of the axis of one of the selectors showing the operative position of the latter under one adjustment;

Figure 8 is a sectional view similar to that of Figure 7 but showing the selector under axial movement of the mover;

Figure 9 is a detail perspective view of a selector;

Figure 10 is a collective elevational and plan view of the selector adjusting key;

Figure 11 is a front elevational view of a second form of the invention;

Figure 12 is a rear elevational view of the same;

Figure 13 is a view similar to that of Figure 11 but broken away to expose the interior;

Figure 14 is a sectional view on the plane indicated by the line 14—14 of Figure 11;

Figure 15 is a view similar to that of Figure 14 but showing the selector in the position to which it has been advanced; and

Figure 16 is a sectional view on the plane indicated by the line 16—16 of Figure 14.

2

Primarily the invention comprises two relatively movable members, a mover and a stator, of which one is fixed with respect to the closure to be controlled and the other is to be operatively connected with the bolt or other latching means by which the closure is retained in closed position.

In that form of the invention illustrated in Figures 1 to 10, the stator 21 is of ring form and the mover 20 is mounted for angular or turning movement in it, such movement, however, as hereinafter explained, is limited to that necessary for the connected bolt or latching means to function. But relative turning movement of the mover and stator is possible only when the tumblers 22 are released, these being small balls caged in pockets 23 in the mover. The tumbler balls are ejectible from the pockets into grooves 24 on the inner periphery of the stator ring, these grooves being axially arranged and having the same angular spacing as the pockets. Ejection is effected through the instrumentality of the selectors 25 which are cross-sectionally circular and are mounted in bores 26 of the mover. On the under sides, the pockets open laterally into the bores and the tumblers, when tangential to the selectors, enter the grooves 24, thus precluding relative angular or turning movement of the mover and stator.

But while the selectors effect ejection of the tumblers into the grooves 24, they also, when properly positioned, permit recession of the former, so that the same may be free of the grooves, thereby removing the restraint to turning movement of the mover. To this end, the selectors are each provided with the clearance seats 27 and 28 both axially and angularly spaced, the angular spacing being preferably ninety degrees and the axial spacing that corresponding to the permissible axial movement of the selectors. Adjustment of the selectors is effected angularly but their operation is effected axially, that is, the selectors are initially set so that on some the seats 27 function while on the remainder it is the seats 28. To provide for such, the selectors are each formed with a pair of parallel axially arranged grooves 29 one of which is diametrically opposite the clearance seat 27 and the other similarly positioned with respect to the seat 28. The adjustment to effect functioning of the selected seat is accomplished by means of a key composed of a post 30, a finger-piece 31 at one end thereof and a pair of spaced prongs 32 at the other end. The post is of the same diameter as the selectors so as snugly to enter the bores in which they are mounted, when the prongs 32 enter the grooves 29 straddling the intervening rib 33.

Turning the key, after having been once placed, effects turning of the selector. To insure the retention of any selector in position for presentation of a clearance seat to its associated tumbler, a globular detent 34a, pressed by a spring 35a, is arranged in the mover diametrically opposite each tumbler and invades the bore in which the selector is carried, thus being in position to enter one or the other of the grooves 29, depending on the adjustment of the selector, which adjustment is effected against the pressure of the detent, the latter receding as the selector is turned. Either groove 29 engaged by a detent, while maintaining the angular position of the selector, does not impede axial movement thereof.

Axial or operating movement is imparted to the selectors through digital members 34 which when pressed bear on the heads 35 of the selectors, are flanged, as indicated at 36, are biased by the springs 37 compressed between the flanges and the bands 38 encircling the heads, and are housed in counterbores 39 formed in the cap-block 40 of the mover. The terminals of the digital members protrude through openings in the cap-block and the flanges 36 bear against the shoulders formed at the inner ends of the counterbores, thus limiting outward movement of the digital members, the inward movement of which is limited by a striking-plate 41, the selectors extending through the striking-plate and the heads 35 impacting it when the selectors are actuated.

The striking-plate is stationary axially with respect to the stator, seating, as indicated at 42, on a shoulder resulting from counter-boring the stator from the outer end. It is also stationary angularly with respect to the mover, being keyed to the latter by diametrically opposite feathers 43 engaged in slots formed in the ring-flange 44 with which the mover is provided. This construction makes for relative axial movement only of the striking-plate and mover and for relative angular movement only of the striking-plate and stator, which latter movement is limited to the angular spacing of the tumblers by a stop 45 carried by the stator which abuts either end of a recess 46 formed in the striking-plate by removing a segment from the periphery of the latter.

The cap-block 40 whose diameter is the same as that of the striking-plate has a central boss 47 of an exterior diameter corresponding to the interior diameter of the ring-flange. This boss enters the ring-flange when the mover and cap-block are assembled and a cap-screw 48 passing centrally through the mover and threading into the boss maintains the assembled relation, pins 49 on the edge of the ring-flange entering holes in the cap-block to ensure axial alignment of the digital members and selectors.

On the obverse side of the mechanism, the digital members, and on the reverse side, the selectors are identified with suitable characters, such as cardinals, so that a selected combination may be readily made and thereafter identified.

In the operation of the invention, it must be borne in mind, when adjusting the selectors, that the clearance seats 28 lie in the plane of the tumblers when the selectors are in their retracted positions and that the seats 27 lie in this plane when the selectors are in their projected or forward positions. Therefore, if all the selectors are positioned with the seats 28 registering with the slots 24, angular movement of the mover in the stator will be possible without actuation of any selector. Conversely, if all the selectors are po-

sitioned with the seats 27 in registration with the slots 24, all must be actuated, if angular movement of the mover is to be possible. The selectors therefore must have relatively different positions if the combination is to function and adjustment for such consists in turning, by means of the key 30, one or more of the selectors, after which some will have the seats 28 registering with the slots 24 and the remainder will have the seats 27 so registering. If all of the selectors then be retracted (which is their normal position), those having their seats 27 set to function will prevent the tumblers from receding from the slots 24 and the mover will be prevented from turning. But depressing the digital members of these selectors will actuate (axially move) the latter, so that the seats 27 will be brought into the plane of the tumblers, thereby allowing the same to recede. Then the mover may be turned the angular distance permitted by the recess 46 in the striking-plate, a distance sufficient at least to advance the tumblers to the next succeeding slots 24 and a distance sufficient to actuate any connected bolt or other latching device.

The mechanism is susceptible of relocking after any angular movement of the mover and this is accomplished by moving the mover axially, a limited movement of this character being possible since the boss-ring-flange connection between the mover and the cap-block spaces the latter slightly from the former to permit axial movement between the whole and the striking-plate.

After any operation of the mover, when some of the selectors will be retracted and the others will have been projected, bodily axial movement of the mover will advance the retracted selectors until their heads impact the striking-plate and the projected selectors will remain stationary, being restrained by the striking-plate. The selectors will thus be brought into positions where their extremities are respectively in common planes, but where their functioning clearance seats are in different planes.

The axial movement of the mover is opposed by all of the springs 37 which return the mover to its normal position after the actuating pressure has been removed. The relative positions of the selectors effected in the axial movement of the mover are retained in the return of the mover, since the detents 34a preclude any movement of the selectors from any inherent cause.

The slots 24 permit the sliding of the tumblers along them in the axial movement of the mover and the bands 38 shield the shoulders formed where the heads 35 join the selectors thus preventing the ends of the springs finding their way under the shoulders and interfering with the free operation of the selectors.

Any selector may be angularly adjusted to dispose both its clearance seats out of registration with its associated slot 24. In such a case the detent 34a will bear peripherally on the selector and the latter will hold its tumbler engaged in its associated slot. The mechanism will then be locked against operation in any manner until the return of the selector to a position where its detent will engage a slot 29. There are conditions under which this expedient will be found to have utility.

In that form of the invention illustrated in Figures 11 to 16, the mover is in the form of a bolt 50, and the stator in the form of a block 51 in which the bolt is slidably mounted and from one end of which it may be projected when the finger-piece 52 is rotated. The finger-piece is at-

tached to a shaft 53 rotatably mounted in the cap-block 54 and carrying on its inner end a collar 55 whose radially projecting fork 56 straddles a pin 57 with which the bolt is equipped.

In this form of the invention, the tumbler grooves are in the mover, being uniformly spaced peripheral grooves 58 in which the spherical tumblers 59 are held to preclude movement of the bolt and from which they are released to permit bolt operation. The tumblers are caged in pockets 60 in the stator which pockets communicate both with the bolt slide-channel and with the selector bearings. The selector bearings are formed in and spaced along the stator in accordance with the spacing of the grooves 58.

The selectors 61, the digital members 62, the compression springs 63 and the detents 64 are identical in function and form with their counterparts heretofore described in detail. And the angular adjustment of the selectors determines which ones are to be moved axially to effect release of the bolt for knob operation.

In this form of the invention, the selectors are not returned to their original positions as in the form first described but by a finger-bar 65 movable in a guide-channel in the under face of the cap-block 54. The finger-bar is exteriorly exposed through a slot in the cap-block and is flanged, as shown at 66, to prevent ejection from the cap-block by the biasing springs 67.

The stator is formed with transverse slots having arcuate bottoms, so as to receive and permit rocking of the rockers 68 which are in the form of Woodruff keys of which one end of each is in position to engage the shoulder formed by the head of each selector and the other ends are in position to be engaged by the finger-bar. When a selector is actuated, the adjacent end of its rocker is depressed and the opposite end is raised. When the finger-bar is actuated, reverse movement is imparted to the rockers with the result that any previously actuated selector is returned to its original position. Thus the finger-bar functions to accomplish the same result that is accomplished by bodily axial movement of the mover in the form shown in Figures 1 to 10.

The cap-block is secured to the stator by screws, as shown at 69, or other appropriate fastening means.

The invention having been described what is claimed as new and useful is:

1. A combination lock comprising operatively connected relatively movable members, a plurality of tumblers carried by the one and engageable in seats formed in the other, axially movable selectors mounted in one of said members and engageable with the tumblers to hold the latter in seat-engaging position, the selectors having clearance seats into which the tumblers may recede to be free of the seats in the seat-carrying member, and means carried by one of the members for imparting axial movement singly to the selectors either to present clearance seats to the tumblers or to retain the latter in the seats of the seat-carrying member.

2. A combination lock comprising operatively connected relatively movable members, a plurality of tumblers carried by the one and engageable in seats formed in the other, movable selectors mounted in one of said members and engageable with the tumblers to hold the latter in seat-engaging position, the selectors having clearance seats into which the tumblers may recede to be free of the seats in the seat-carrying member, and means carried by one of the members for

imparting axial movement singly to the selectors either to present clearance seats to the tumblers or to retain the latter in the seats of the seat-carrying member, the selectors being mounted to permit angular movement being imparted to any one to determine if axial movement be necessary to present a clearance seat on a particular selector.

3. A combination lock comprising operatively connected relatively movable members, a plurality of tumblers carried by the one and engageable in seats formed in the other, axially and angularly movable selectors mounted in one of said members and engageable with the tumblers to hold the latter in seat-engaging position, the selectors having clearance seats into which the tumblers may recede to be free of the seats in the seat-carrying member, means for imparting axial movement singly to the selectors either to present clearance seats to the tumblers or to retain the latter in the seats of the seat-carrying member, the selectors being mounted to permit angular movement being imparted to anyone to determine if axial movement be necessary to present a clearance seat on a particular selector, and means incorporated in one of the members for simultaneously restoring the selectors to their original positions after actuation of any or all of them.

4. A combination lock comprising operatively connected relatively movable members, a plurality of tumblers carried by the one and engageable in seats formed in the other, axially movable selectors mounted in one of said members and engageable with the tumblers to hold the latter in seat-engaging position, the selectors having clearance seats into which the tumblers may recede to be free of the seats in the seat-carrying member, and means carried by one of the members for imparting axial movement singly to the selectors either to present clearance seats to the tumblers or to retain the latter in the seats of the seat-carrying member, and means incorporated in one of the members for simultaneously restoring the selectors to their original positions after actuation of any or all of them.

5. A combination lock comprising operatively connected relatively movable members, a plurality of tumblers carried by the one and engageable in seats formed in the other, axially and angularly movable selectors mounted in one of said members and engageable with the tumblers to hold the latter in seat engaging position, the selectors each having angularly and axially spaced clearance seats into which the tumblers may recede to be free of the seats in the seat-carrying member, and means carried by one of the members for singly imparting axial movement to the selectors, the selector being angularly adjustable to determine in each the clearance seat to be presented to its associated tumbler.

6. A combination lock comprising operatively connected relatively movable members, a plurality of spherical tumblers carried by the one and engageable in seats formed in the other, axially movable selectors mounted in one of said members and peripherally engageable with the tumblers to hold the latter in seat engaging position, the selectors having each a clearance seat into which its associated tumbler may recede to be free from the seat of the seat-carrying member, an axially movable spring pressed digital member for each selector, and means incorporated in one of the members for simultaneously

restoring the selectors to their original positions after actuation of any or all of them.

7. A combination lock comprising operatively connected relatively movable members, a plurality of spherical tumblers carried by the one and engageable in seats formed in the other, axially and angularly movable selectors mounted in one of said members with each engageable with a tumbler to hold the latter in seat-engaging position, the selectors having each angularly and axially spaced clearance seats into which the tumblers may recede to be free of the seats in the seat-carrying member, and means carried by one of the members for singly imparting axial movement to the selectors, each selector being angularly adjustable so that one or the other of its clearance seats will be presented to its associated tumbler, and means yieldingly retaining the selectors in their angularly adjusted positions without prevention of axial movement of the same.

8. A combination lock comprising operatively connected relatively movable members, a plurality of spherical tumblers mounted in the one and engageable in seats formed in the other, angularly and axially cross-sectionally circular movable selectors mounted in one of said members and tangent to the tumblers to maintain the latter in seat engaging position, the selectors each having axially and angularly spaced clearance seats into which the tumblers may recede to be free of the seats in the seat-carrying member, means carried by one of said members for singly imparting axial movement to the selectors, the selectors being angularly adjustable for clearance seat selection, and spring pressed means bearing radially on each selector yieldingly to maintain its angularly adjusted position without impeding its axial movement.

9. A combination lock comprising operatively connected relatively movable members, a plurality of spherical tumblers mounted in the one and engageable in seats formed in the other, angularly and axially movable cross-sectionally circular selectors mounted in one of said members

and tangent to the tumblers to maintain the latter in seat engaging position, the selectors each having axially and angularly spaced clearance seats into which the tumblers may recede to be free of the seats in the seat carrying member and each also having spaced parallel grooves extending in the direction of the length thereof, means carried by one of the members for singly imparting axial movement to the selectors, the selectors being angularly adjustable to determine the clearance seat for tumbler recession, and a spring pressed retention member for each selector and engageable in one or the other of said grooves to maintain the angular adjustment of the selector without impeding its axial movement.

10. A combination lock comprising operatively connected relatively movable members, a plurality of spherical tumblers mounted in the one and engageable in seats formed in the other, angularly and axially movable cross-sectionally circular selectors mounted in one of said members and tangent to the tumblers to maintain the latter in seat engaging position, the selectors each having axially and angularly spaced clearance seats into which the tumblers may recede to be free of the seats in the seat carrying member and each also having spaced parallel grooves extending in the direction of the length thereof, means carried by one of said members for singly imparting axial movement to the selectors and engageable in one of the other of said grooves to maintain the angular adjustment of the selector without impeding its axial movement, the grooves being disposed one diametrically opposite one clearance seat and the other being positioned similarly with respect to the other clearance seat.
